UNITED STATES PATENT OFFICE.

STEPHEN M. WIRTS, OF DETROIT, MICHIGAN, AND EDWARD L. DUCKWALL, OF SALEM, INDIANA, ASSIGNORS TO AMERICAN GRAPHOPHONE COMPANY, OF BRIDGEPORT, CONNECTICUT, A CORPORATION OF WEST VIRGINIA.

DESIGN FOR A CABINET FOR TALKING-MACHINES.

44,993.

Specification for Design.

Patented Dec. 2, 1913.

Application filed October 9, 1912. Serial No. 724,852. Term of patent 14 years.

To all whom it may concern:

Be it known that we, STEPHEN M. WIRTS and EDWARD L. DUCKWALL, citizens of the United States, and residents of Detroit, in the county of Wayne and State of Michigan, and Salem, in the county of Washington and State of Indiana, respectively, have invented a new, original, and ornamental Design for a Cabinet for a Talking-Machine, reference being had to the annexed drawing, forming part hereof, which is a perspective view of a cabinet embodying our design aforesaid.

We claim:

The ornamental design for a cabinet for a talking-machine, as shown.

In testimony whereof we have signed this specification in the presence of two subscribing witnesses.

STEPHEN M. WIRTS.
EDWARD L. DUCKWALL.

Witnesses to Wirts's signature:

WILLIAM A. HURST,
H. M. RANSOM.

Witnesses to Duckwall's signature:

OSBORNE E. COFFMAN,
HOMER MARTIN.
